Specification for Design.

Patented Aug. 6, 1912.

Application filed April 12, 1912. Serial No. 690,366. Term of patent 7 years.

● *To all whom it may concern:*

Be it known that I, LOUIS B. LONDON, a citizen of the United States, residing in the borough of Manhattan, city of New York, county and State of New York, have invented a new, original, and ornamental Design for Inverted Gas-Burners, of which the following is a specification, reference being had to the accompanying drawings, forming part thereof.

Figure 1 of the drawings is a side elevation and Fig. 2 is a top plan view of an inverted gas burner, showing my new design.

I claim:

The ornamental design for an inverted gas burner, as shown.

In testimony whereof, I have hereunto set my hand in the presence of the two subscribing witnesses.

LOUIS B. LONDON.
